Primary Examiner — Elizabeth J Oswecki*(74) Attorney, Agent, or Firm* — Muncy, Geissler, Olds & Lowe, P.C.(57) **CLAIM**

The ornamental design for a tree stand, as shown and described.

DESCRIPTION

FIG. 1 is a perspective view of a tree stand showing my new design;

FIG. 2 is a top plan view thereof;

FIG. 3 is a bottom plan view thereof; and,

FIG. 4 is a front elevational view thereof, the rear elevational view, left side elevational view, and right side elevational view being identical.

The broken lines shown in the drawings represent portions of the tree stand that form no part of the claimed design.

1 Claim, 4 Drawing Sheets(56)
